UNITED STATES PATENT OFFICE

RUSSELL V. JUDSON, OF DETROIT, AND CHARLES C. DAVIS, OF FENTON, MICHIGAN,
AND EDWIN O. KLEMM, OF CICERO, ILLINOIS

RADIO RECEIVING APPARATUS

Application filed September 8, 1924. Serial No. 736,522.

The purpose of this invention is to provide a simple form of mounting for radio receiving apparatus by which it may be readily installed in a variety of styles of phonograph cabinets and the like of either the upright or console type, such mounting being adapted to permit ready removal of the radio unit from the cabinet for inspection or repair without danger of injury to the apparatus. The invention has the further object of arranging the controls upon an adjustable panel which may be secured at an oblique position convenient to the operator in "tuning" the receiving set. It consists of certain features and elements of construction in combination as hereinafter shown and described and as particularly indicated in the appended claims.

In the drawings:

Figure 1 is a front elevation of a phonograph cabinet having a radio receiving set installed in accordance with this invention.

Figure 2 is a horizontal section taken substantially as indicated at line 2-2 on Figure 1.

Figure 3 is a vertical section taken as indicated at line 3-3 on Figure 1.

Figure 4 is a fragmental detail view of an improved multiple connector for the circuit wires.

Figure 5 is an enlarged detail view partly in section taken as indicated at line 5-5 on Figure 3.

Figure 6 is a detail section taken as indicated at line 6-6 on Figure 5.

Figure 7 is a vertical section similar to Figure 3 showing a modification.

Figure 8 is a vertical section similar to Figure 3 showing another modification.

Figure 9 is also a section similar to Figure 3 showing a third modification.

Figure 10 is likewise a vertical section showing a fourth modification of the invention.

For the purposes of illustration we have chosen a cabinet of the so-called console type which is divided by a partition, 1, into two compartments, one of which may enclose a phonograph mechanism whose winding crank is shown at 2 and whose horn or amplifier, 3, occupies the lower portion of the com-

partment, having a grille, 4, through which the sound escapes into the room. A front panel, 5, for enclosing and concealing the grille, 4, is indicated in Figure 1. At the rear of the compartment the amplifier, 3, is contracted and curved upwardly to form a sound conduit, 6, leading from the usual tone arm and phonograph reproducer not shown. The other half of the cabinet is used to house the radio receiving apparatus and the majority of this apparatus is mounted on a special panel which is shown as a sheet, 7, of thin ply-wood or other suitable material such as vulcanized fibre, "condensite" or some synthetic substance. The sheet, 7, is mounted in a frame, 8, as shown in Figures 2 and 3 and it supports at the rear side a shelf, 9, extending at right angles from the plane of the sheet, 7. Figure 2 shows a tuning coil, 10, and a vario-coupler, 11, mounted on the shelf, 9, and Figure 3 indicates the arrangement of the one or more vacuum tubes, 12, in sockets, 13, on the under side of said shelf. The control dials, 14, and knobs, 15, are disposed at the front side of the panel, 7,—one of the dials being indicated as connected to the variable condenser, 16, at the rear side of the panel and the other dial being connected for adjusting the vario-coupler, 11. It may be understood that other units of apparatus than those indicated may be substituted to provide any desired hook-up without departing from the spirit of this invention. A fixed shelf, 17, extends forwardly into the compartment from the rear wall of the cabinet and may be utilized to support a storage battery, 18, as shown in Figure 2, space being afforded below the shelf, 17, for the other battery usually required.

The panel, 7, is pivotally supported in the opening at the front of the left hand compartment by means of pivot pins, 19, projecting horizontally at the margins of the opening to engage downwardly open hooks, 20, which are secured to the rear faces of the frame members, 8, of the panel. In the arrangement shown in Figure 3 the pins, 19, are located near the upper edge of the opening so that the panel may be swung into oblique position with its lower edge entirely 10.

out of the cabinet, thus bringing the dials, 14, to a convenient angle for reading and adjustment by a person seated or standing in front of the cabinet. A brace member, 21, 5 may be hinged to the lower frame member, 8, of the panel with its opposite end trailing between guides, 22, as the panel is swung forwardly so that the down-turned portion, 23, of said trailing end of the brace may engage 10 in a retaining notch of the fitting, 24, as shown in Figure 3. For returning the panel to vertical position it is only necessary to lift the brace, 21, slightly to free it from the notch in the part, 24, and thus allow the panel to 15 swing back.

When the apparatus is associated with the phonograph it is a simple matter to utilize the amplifying horn, 3, of the phonograph in connection with the telephone receiver, 24, 20 by mounting the latter over a short branch, 25, extending laterally from the conduit, 6, so that the sound waves set up by the telephone diaphragm may be transmitted to the air in the conduit, 6, and amplified in the 25 same manner in which the vibrations originating at the phonograph diaphragm are increased in volume. Preferably the telephone, 24, the batteries and the aerial and ground wires, 26 and 27, which are shown entering the 30 back of the cabinet are detachably connected to the apparatus carried on the panel, 7. For this purpose the shelf, 9, has a series of binding screws, 28, each associated with a contact blade, 29, and the wires from the various 35 pieces of apparatus carried by the panel are connected to these binding screws. A support, 30, preferably made of the same insulating material as the panel, 7, carries a row of corresponding contact blades, 31, to which are 40 attached the various wires leading to the fixed elements of the set such as the telephone and batteries. The hooks, 20, being downwardly opened are readily disengaged from the pivot pins, 19, when the panel is swung to oblique 45 or horizontal position and then to permit complete removal of the panel and its associated apparatus it is only necessary to withdraw the support, 30, from the shelf, 9, thus slidably disengaging the blades, 31, from 50 the blades, 29, with which they interlap in connected position. The relation of the parts immediately following such disconnection is shown in Figure 4.

Figure 7, being a section somewhat similar 55 to Figure 3, illustrates the same type of cabinet but the units of the receiving set are differently supported. A panel, 40, completely fills the opening at the front of the compartment in which the set is housed and near its lower edge said panel supports a second panel, 41, of less area and attached to the panel, 40, at a slightly acute angle. The panel, 40, is mounted in the cabinet by means of hooks, 20, 60 engaging pivot pins, 19, but is intended to be 65 swung through a wide angle to the dotted line

position shown in Figure 7 at which it is supported by a stay hook, 42, engaging a pin, 43, in the side wall of the compartment. This position of the panel, 40, brings the panel, 41, to approximately vertical position, preferably somewhat inclined to facilitate reading 70 of the dials, 14, which are carried by the panel, 41, with which are associated the control knobs, 15, of the apparatus. This arrangement has the advantage of swinging the 75 knobs and dials to a slightly higher position than when they are mounted as shown in Figure 3 and also of moving them farther from the cabinet itself, leaving better knee space for the operator if he sits in front of 80 the panel, 41.

Figure 8 shows an arrangement more nearly similar to that of Figure 3 in which a single panel, 50, supports all the units of the apparatus directly on its rear face while the 85 control knobs, 15, are accessible at the forward side of the panel. A pair of special arcuate supporting brackets, 51, extend from the rear face of the panel, 50, with their slots, 51, engaging guide studs, 52 and 53, so that 90 the slots, 51, track over said studs as the panel is drawn forward to the inclined position shown in dotted lines. At the limit of such position the hook-shaped end of each slot, 51, engages the rear stud, 52, for supporting the 95 panel thus obliquely extended. This presents the dials, 14, in easily readable position and when the receiving set is out of use the panel and units attached thereto are easily pushed back into the compartment of the cabinet 100 after first slightly tilting the panel, 50, to release the hooked end of the slot, 51, from the post, 52.

In Figure 9 the arrangement of the parts is inverted as compared with Figure 7, the 105 front panel, 60, being supplemented by a smaller panel, 61, supported at an acute angle near the upper edge of the panel, 60, so as to present the dials, 14, and knobs, 15, for access 110 when the upper edge of the panel, 60, is drawn forward from the cabinet. Near the lower edge the panel, 60, is fitted with hooks, 20, engaging pivot studs, 19, to form a hinge. At its forward limit the panel, 60, is retained 115 by a hook, 62, engaging the stud, 63, in the side wall of the compartment. The units of the apparatus are distributed upon the inner walls of the panels, 60 and 61, as convenience 120 may dictate.

Figure 10 illustrates the same pair of dials, 120 60 and 61, as shown in Figure 9, but with the hooks, 20, and pivot studs, 19, located at about the middle of the height of the panel, 60, so that as its upper edge is tilted forward the panel, 61, is brought to a more steeply inclined position approaching the vertical but still sufficiently tilted to facilitate reading of the dials, 14, and operating the knobs, 15.

It will be seen that with any of the described arrangements the installation of the 130

radio receiving set in a phonograph cabinet of standard design requires merely the application of two or three simple fittings such as the pivot studs, 19, and a guide way, 22, and that after such installation the radio set can be very easily and quickly removed from the cabinet for repair or adjustment.

Figure 6 shows a special form of safety switch comprising a fixed contact, 70, and a spring contact arm, 71, mounted on a corner post, 72, of the cabinet just inside the door, 73, which closes the compartment containing the radio apparatus. A plunger, 74, is guided in the post, 72, so that when the door, 73, is closed it will engage the protruding end, 75, of the plunger, 74, and force the latter inwardly to lift the spring member, 71, out of contact with the part, 70. Lead wires extend from the switch to the battery connections so that whenever the cabinet is completely closed in this manner the battery circuit will be opened, thus avoiding overheating or unnecessary use of the vacuum tubes, 12.

We claim:—

1. In combination with a radio receiving set, a cabinet for housing the apparatus, said cabinet having an opening at one side with a panel fitted in the opening standing normally in a vertical plane but mounted for swinging outwardly about a horizontal axis, said panel supporting certain units and control members of the apparatus; and means adapted to limit the swing of the panel at a position in which the control members are presented in an inclined plane which extends upwardly and away from the operator at a convenient angle for manipulation.

2. In combination with a radio receiving set, a cabinet for housing the apparatus having an opening at one side; a panel fitted in the opening and standing normally in a vertical plane; certain units of the apparatus being mounted on the inner side of said panel with control members accessible at the outer side, the panel being mounted for swinging outwardly about a horizontal axis near its upper edge into an inclined position to facilitate handling of the control members and means for retaining the panel at such inclined position.

In testimony whereof, we have affixed our signatures to this specification.
